UNITED STATES PATENT OFFICE.

HENRY CÔTÉ, OF WEST WARREN, MASSACHUSETTS, ASSIGNOR TO WARE MACHINE & LOOM COMPANY, OF WARE, MASSACHUSETTS, A CORPORATION OF MASSACHUSETTS.

PICKER-CHECK.

1,023,197.

Specification of Letters Patent.

Patented Apr. 16, 1912.

Application filed November 21, 1910. Serial No. 593,375.

To all whom it may concern:

Be it known that I, HENRY CÔTÉ, a citizen of the United States, residing at West Warren, county of Worcester, State of Massachusetts, have invented an Improvement 5 in Picker-Checks, of which the following description, in connection with the accompanying drawing, is a specification, like characters on the drawing representing like parts.

This invention relates to picker checks and especially to that type of picker check which is associated with the rocker foot of the loom.

The objects of my invention are to provide a simple and inexpensive picker check which can be readily applied to any loom employing a rocker foot, and which will effectively act to check the movement of 20 the picker in both directions.

I will first describe some embodiments of my invention and then point out the novel features thereof in the appended claims.

Referring now to the drawings, Figure 1 25 shows the rocker foot, rocker and portion of the picker stick of a loom having one embodiment of my invention applied thereto; Fig. 2 is a similar view showing a different embodiment of the invention; Fig. 30 3 is a section on the line $x-x$, Fig. 1.

I have not deemed it necessary herein to illustrate any portion of the loom except the rocker foot, rocker and lower end of the picker stick, as the principle and operation 35 of the invention will be readily understood by those skilled in the art without showing any other parts of the loom.

In the drawing 3 designates a portion of the loom frame, 4 the usual rock-shaft suspended therein, 5 the rocker foot carried on the end of the rock-shaft, and 6 the rocker which operates on the rocker foot, and 7 the picker stick which is secured to the rocker 6 in usual way by bolts or other fastenings 8. These parts may be of any suitable or usual construction and form no part of my present invention. Associated with the picker stick is a member 9 which in some respects corresponds to the part 45 commonly known as the "rocker tongue." This member is a metal strap member secured to the side of the picker stick and extending down through the rocker and rocker foot. At its lower end it is bent laterally to form the seat portion 10 in

which is received a cushion device 11, as shown and described in a co-pending application filed on January 26, 1910, jointly by myself and R. C. Snow, Se. No. 536,679, which cushion device is adapted to act 60 against the under side of the rocker foot, thereby to check and limit the swinging movement of the picker stick in both directions, all as described in said application.

In my present improvement, I provide 65 the member 9 with the extension 12 which is acted upon by a spring 13 that tends to throw the picker stick into its backward position, as shown in Fig. 1, and which spring takes the place of the ordinary heel 70 strap spring. In the embodiment of the invention shown in Fig. 1 this spring 13 encircles a rod 14 which extends through the extension 12 and which is supported in some suitable way by the rocker foot 5. The 75 heel strap spring is usually supported in a lug 15 which is formed on and depends from the rocker foot 5, and in the embodiment shown in Fig. 1, the rod 14 is adapted to be sustained in this lug, and for this 80 purpose said rod is provided with an upwardly-bent portion 16 and a laterally-bent portion 17, said portion 17 being secured in the lug 15 by suitable set nuts 18. The rod 14 carries an adjustable collar 19 against 85 which the spring 13 abuts.

In the operation of the device when the picking mechanism is actuated to give the picker stick its operative movement, the rocker 6 will rock over the rocker foot 5 90 in usual manner, and in doing so the spring 13 will be compressed more or less. Said spring 13 will thus act as a means to check the forward movement of the picker stick and the movement of the stick is limited by 95 the engagement of the cushion device 11 with the underside of the rocker foot, it being understood that when the picker stick is in an intermediate position the cushion device 11 does not engage the underside of 100 the rocker foot, but only has engagement therewith when the picker stick is in either of its two extreme positions. This cushion device 11 together with the spring 13 are so arranged that they will check the movement of the picker stick before the latter can strike the end of the slot in the shuttle box, and thus the forward movement of the picker stick will be checked without any 105 damage thereto. The tension of the spring 110

13 tends to return the picker stick to its normal position, and when the shuttle is thrown and strikes the picker the backward movement of the picker stick will be limited 5 by the engagement of the cushion member 11 with the underside of the rocker, as shown in Fig. 1.

The device shown in Fig. 1 is adapted to be applied to the rocker foot as now commonly constructed with the lug 15 designed 10 to support the heel strap spring; but by means of my invention it is not necessary to use the heel strap spring.

In Fig. 2 I have shown another embodiment of my invention in which a spring is employed for checking the movement of the picker stick in both directions. As herein shown, the spring 130 is sustained by a rod 140, which instead of being carried by the 20 lug 15 is supported by a boss or lug 150 formed on the hub of the rocker foot 5. The spring 130 is confined between an adjustable collar 19 on said rod and the extension 12 as in the embodiment of the 25 invention shown in Fig. 1, and another spring 20 is situated between the extension 12 and the hub 150. The spring 13 assists in checking the forward movement of the picker stick, and the spring 20 assists in checking 30 the backward movement thereof.

In Fig. 1 I have shown the seat 10 as formed with the upwardly-directed portion 21 between which and the body of the member 9 the cushion member 11 is inserted. In 35 Fig. 2 this upwardly-directed portion 21 is omitted and the cushion member 11 is held in place by a rivet or pin 22 which fastens said cushion member to the seat.

Having fully described my invention, 40 what I claim as new and desire to secure by Letters Patent is:—

1. In a picker check, the combination with a rocker foot, of a rocker thereon, a picker stick secured to the rocker, a seat portion 45 extending laterally from the picker stick beneath the rocker foot, a cushion member sustained on said seat and adapted to engage the under side of the rocker foot to check the movement of the picker stick, an extension from said seat, and a spring acting on 50 said extension.

2. In a picker check, the combination with a rocker foot, of a rocker thereon, a picker

stick secured to the rocker, a seat portion 55 extending laterally from the picker stick beneath the rocker foot, a cushion member sustained on said seat and adapted to engage the under side of the rocker foot to check the movement of the picker stick, said seat having a downward extension, a 60 rod carried by the rocker foot and extending through said extension, and a spring on the rod acting against the extension.

3. In a picker check, the combination with a rocker foot having a picker stick-receiving aperture, of a rocker thereon, a picker stick secured to the rocker and extending through said aperture in the rocker foot and below the latter, a plate secured to the picker stick and extending through the aperture in the rocker foot and below the lower end of the picker stick, the extending end of said plate being slotted, a rod rigidly secured to the inner end of the rocker foot and extending horizontally through the slot 75 of said extension, a spring on the rod acting on the extension, and an adjustable collar on the outer free end of the rod against which the spring acts and by means of which its tension may be varied. 80

4. In a picker check, the combination with a rocker foot having a picker-stick-receiving aperture, of a rocker thereon, a picker stick secured to the rocker and extending through said aperture in the rocker foot 85 and below the latter, a plate secured to the picker stick and extending through said aperture in the rocker foot and below the lower end of the picker stick, the extending end of said plate being slotted, a rod rigidly secured to the inner end of the rocker foot and extending horizontally through the slot of said extension, a spring on the rod acting on the extension, an adjustable collar on the outer free end of the rod against which the 90 spring acts and by means of which its tension may be varied, and another spring confined between said extension and rocker foot.

In testimony whereof, I have signed my name to this specification, in the presence of 100 two subscribing witnesses.

HENRY CÔTÉ.
